UNITED STATES PATENT OFFICE

ROMEO A. DE BUCCI, OF PROVIDENCE, RHODE ISLAND

COAT AND TROUSER HANGER

Application filed April 11, 1932. Serial No. 604,541.

This invention relates to coat and trouser hangers, and has for its object the production of a simple and efficient coat and trouser hanger, wherein the device is provided with an efficient clamp for supporting a pair of trousers in firm engagement with the coat hanger.

Another object of this invention is the production of a simple and efficient means for locking the trouser clamp in an adjusted position.

A still further object of this invention is the production of a simple and efficient means for attaching the trouser clamp supporting spring in engagement with the coat hanger, and the trouser clamp, so as to prevent the spring from shifting in its movement and cause the spring to remain in its proper position for clamping engagement.

With these and other objects in view, this invention consists in certain novel constructions, combinations and arrangements of parts as will be hereinafter fully described and claimed.

In the drawing:

Figure 1 is a perspective view of the coat and trouser hanger;

Figure 2 is a vertical central transverse sectional view thereof;

Figure 3 is a section taken on line 3-3 of Figure 2;

Figure 4 is a longitudinal sectional view through a portion of the coat hanger and a portion of the trouser clamp; and

Figure 5 is a detail perspective view of the clamping spring used in connection with the present invention.

By referring to the drawing, it will be seen that 1 designates a coat hanger which may be of any suitable or desired construction, and which may be formed of two sections which are connected and secured together by means of the corrugated plates 2. The hanger hook 3 is secured to the hanger 1, and is provided with a laterally extending terminal 4 for the purpose of holding the hanger hook 3 in a set position, and prevent the hanger hook from being twisted with respect to the hanger 1. The hanger 1 is provided at its terminals with bifurcated por-

tions 5, as shown clearly in Figure 1 of the drawing, and the primary trouser-clamping bar 6 extends across and spans the terminals 7 of the hanger 1, as shown clearly in Figure 1. This primary clamping bar 6 has its respective ends seated within the bifurcated portion 5 of the terminals 7 of the hanger 1, as shown, and the ends of this primary clamping bar 6 may be secured by means of suitable securing pins 8. The primary clamping bar 6 is moved laterally as indicated at 9 intermediate the ends thereof to permit the accumulation of material therein between the respective ends of the adjustable or clamping jaw 10.

The adjustable or clamping jaw 10 is provided with a laterally bowed portion 11, as shown, and is also provided with a pair of laterally projecting clamping fingers 12, which clamping fingers 12 are adapted to fit flat against the straight portion 13 of the primary clamping bar 6.

A supporting spring for the primary clamping bar 6 and the adjustable clamping bar 10 is provided, and comprises a wire strand having an upper loop portion 14 which fits snugly within the receiving socket 15 formed in the underface of the hanger member 1. This loop portion 14 by fitting in the socket 15 snugly, will hold the spring 16 in a set position and against twisting movement. The spring 16 is provided with a stationary leg 17 which leg is provided at its lower end with a loop or eye portion 18 extending at right angles to the loop 14, or extending longitudinally of the primary clamping bar 6. This loop or eye 16 fits snugly within a socket 19 formed in the primary clamping bar 6, as shown, and is firmly held against accidental removal from the socket 19 by means of a suitable securing pin 20.

As shown clearly in the drawing, the spring 16 is also provided with an adjustable leg 21 depending from the loop portion, and this adjustable leg 21 is provided with a series of suitable corrugations 22, the lower extremity of the adjustable leg 21 being provided with an eye or loop portion 23, this loop portion or eye 23 extending at right-angles to the loop 14. The eye portion 23 is mounted

within a socket 24 formed in the adjustable clamping member or jaw 10, as shown clearly in Figures 1 and 2 of the drawing, and the eye or loop portion 23 is firmly held within the socket 24 by means of an anchoring pin 25. A slideable link 26 is slidably mounted over the arm 17, and also over the adjustable arm 21, and is adapted to slide down over the corrugated portion 22 and in this way draw the adjustable leg 21 into a clamped position such as is shown in full line as the link 26 is moved downwardly with respect to the legs or arms 17 and 21. As the link 26 is moved downwardly, the adjustable clamping arm or member 10 will be firmly drawn toward the primary or stationary clamping bar 6 and in this way will permit a pair of trousers, or other article, to be firmly clamped between the spring portions 13 of the primary clamping bar 6, and the projecting fingers or arms 12 of the adjustable jaw 10. It should be understood that the arms or legs 17 and 21 diverge outwardly toward their lower ends to provide for the inward drawing of the arms as the link 26 is moved downwardly from the top toward the bottom of the legs or arms 17 and 21, as clearly shown in Figure 2.

It should be understood that a very simple and efficient means has been provided for supporting the trouser clamp in conjunction with the coat hanger, and that the spring member 16 will be firmly anchored in engagement with the coat hanger 1 by having the loop portion 14 snugly fitting within the socket 15, thereby holding the spring member 16 against rotating movement. Then by having the loop or eye 23 extending at right angles to the loop 14, the arms 17 and 21 will also be held in proper relation so as to retain the corrugated portions 22 of the arms 21 in proper position for engagement with the link 26 and thereby permit the locking of the adjustable jaw 10 with respect to the stationary primary bar 6 as the link 26 is moved down over the various corrugations 22 of the adjustable or clamping arm 21.

It should be understood that certain detail changes in the mechanical construction may be employed without departing from the spirit of the invention so long as these changes fall within the scope of the appended claim.

Having described the invention, what is claimed as new is:

55. A hanger of the class described comprising a coat hanger member, a stationary clamping jaw extended between the ends of said coat hanger member, an adjustable clamping jaw provided with laterally extending substantially aligned arms adapted to be brought into clamping engagement with said stationary clamping jaw, a supporting spring member, said coat hanger member provided with a socket, a loop portion formed upon said spring member snugly fitting in said socket,

70 said spring member provided with a stationary leg having a loop formed at the end thereof extending at right-angles to said first mentioned loop, and engaging said stationary jaw whereby the spring member will be firmly clamped between the stationary jaw and the coat hanger, said spring member provided with a spring adjustable arm having corrugations formed upon the length thereof, the terminals of said spring adjustable arm being provided with a loop extending at right angles to said first-mentioned loop, said adjustable jaw provided with a socket for receiving said loop formed on the terminal of said adjustable arm, and a clamping link slideable over said stationary and adjustable arms of said spring member.

75 In testimony whereof I affix my signature.

ROME A. DE BUCCI.
